Noland J. Davis, Bay City, Mich.

Application October 18, 1954, Serial No. 462,817

9 Claims. (Cl. 15—128)

This invention relates to portable fountain-type brushes having handles which are adapted to be connected to a source of liquid supply, and more particularly to a brush of this type in which the surface engaging portion thereof can be very easily maintained in a position approximately normal to the surface being washed.

Brushes having handles which may be connected to a source of liquid supply under pressure are extensively used today to wash walls, vehicles, and the like; however, such implements have not been entirely satisfactory inasmuch as washers have experienced considerable difficulty in maintaining the brush head in positions in which the bristles are substantially normal to the surface. Obviously, a brush which is normal to the upper surface of a wall will be disposed at an angle to the wall when it is lowered to wash the medial and lower surfaces of the wall unless the washer assumes an incongruous position. Frequently, when surfaces approximately on a level with or below the head of a washer are being scrubbed or, when the surface is curvilinear or irregular, the washer will mar or scratch the surface being cleansed by inadvertently rubbing a portion of the brush device other than the bristles, against the surface being washed, or the trim thereof.

One of the prime objects of the instant invention is to design a brush which can be remotely adjusted without shifting the implement in the hands of the user by simply turning the valve controlling the volume of liquid supplied which is located on the elongated handle of the brush.

Another object of the invention is to design a brush of the type described which is positively maintained in a given position of adjustment during the washing operation and cannot slip out of adjustment.

A further object of the invention is to provide a brush of this type which is very convenient to use and manipulate and which can be efficiently used by inexperienced persons to thoroughly clean various surfaces without marring the finishes thereof.

Another object of the invention is to design a brush of this nature in which the brush head is readily removable from its holder and can be replaced when necessary after long service.

A further object of the invention is to design a brush of the type described in which the washing liquid is sprayed to the upper bristles and therefore will be more efficiently employed by the brush to loosen dirt and the like.

A still further object of the invention is to design a brush of this type which is of sturdy and durable construction and can be very economically manufactured, assembled and sold.

With the above and other objects in view, the present invention consists in the combination and arrangement of parts, hereinafter more fully described, illustrated in the accompanying drawings, and particularly pointed out in the appended claims, it being understood that equivalent changes may be made in the various elements of the

invention, without departing from the spirit, or sacrificing any of the advantages of the invention.

In the drawings:

Fig. 1 is a side elevational view of the brush.

Fig. 2 is a front elevational view thereof.

Fig. 3 is a sectional, side elevational view showing the brush head locked in a position of angular adjustment when liquid is being supplied to the brush.

Fig. 4 is a similar view showing the locking means in disengaged position after the liquid supply has been shut off.

Referring now more particularly to the accompanying drawings in which I have shown a preferred embodiment of the invention, and wherein like reference numerals indicate like parts in accordance with the following description, a numeral B generally indicates a conventional brush which includes the usual bristles 10 mounted in a back 11. To support the brush in engagement with the surface to be scrubbed or washed, I have designed a clamp plate 12 which comprises laterally adjustable lapped or telescoping clamps 12a and 12b, these clamps having flanges 12c which engage the underside of the back of the brush as shown.

Mounted centrally on the plate 12b is a housing 13 including side walls 13a, a rear wall 13b, a bottom wall 13c, and a semi-cylindrical head or upper wall 13d. A tongue 14, fixed on the clamp 12a, extends into the housing 13 and has a nut 14a mounted thereon. A screw 15 threaded through an opening 16 in the rear wall 13b of the housing 30 has threaded engagement with the nut 14a and it will be obvious that the clamp 12a may be moved outwardly or inwardly relative to the clamp 12b by simply actuating the screw 15.

The arrangement of the clamp plate 12 permits brushes of lesser or greater width being accommodated and the clamp plate 12 is not limited to clamping a brush of given dimensions. A fitting 17, which is bifurcated to provide forks 17a, is pivotally mounted on the housing 13 by means of a bolt 18, and as is indicated in Fig. 1, and a 40 cotter pin 19 retains the fitting on the bolt.

The fitting 17 has a collar in which a cylinder 20 is fixed, and a coupling 21 which is interiorly threaded as at 22, connects the cylinder 20 and the elongated tubular handle 23 of the brush, the cylinder and handle being exteriorly threaded as at 24 and 25 respectively and are accommodated in the opposite ends of the coupling 21. The handle 23 which has an outer end connected to a source of liquid supply (not shown) is equipped with a conventional shut off valve 26 to control the quantity of liquid flowing through the handle 23.

The valve 26 includes a lever 27 which may be adjusted to position in which it is shown in Figs. 1 and 3 to open the valve and permit liquid to flow therethrough, and it may be turned to the position in which it is shown in Fig. 4 to shut off the flow of liquid through the handle. From the rigid tube 28 which opens into the interior of the coupling 21 at 29, a flexible tube 30 leads to a tube 31 on an elongated spray nozzle 32 which is fixed on the front wall of the plate 12. Closely spaced apart openings 60 33 in the lower portion of the nozzle direct the liquid to the front bristles 10 in continuous streams or sprays.

Provided in the cylinder 20 is a plunger 34 which extends through the front wall 20a of the cylinder and has a tapered end adapted to engage in one of a plurality of 65 radially spaced notches 35 in the head 13d dependent on the angular position of the brush relative to the handle. A spring 36 normally holds the plunger 34 out of engagement with the head 13d (see Fig. 4), until the pressure of the incoming water or other liquid forces it outwardly into one of the notches.

In practice, the operator may rest the brush B against the surface to be washed and thence pivot the handle

23 about the pin 18 until it is at the desired angle relative to the brush. If the lever 27 is now turned to position shown in Fig. 3, the pressure of the liquid forces the plunger 34 forwardly into the particular notch 35 which is in alignment therewith. The liquid flows through the opening 29, tube 28, flexible tubing 30 and tube 31 into the nozzle 32 and is sprayed, with considerable force, through the openings 33 onto the front bristles of the brush. Since the surface being washed is usually a vertical or vertically inclined surface, the liquid being sprayed must traverse the entire width of the brush and will be used with a maximum efficiency. When the washing operation has progressed to a point where the relative angularity of the brush and handle should be changed, it is only necessary to turn off the liquid momentarily at the lever 27 which permits the spring 36 to retract the plunger 34 from the head 13d. The position of the handle 23 may then be adjusted in the above described manner.

While I have shown the device as particularly useful to clamp a brush, I contemplate that a wiper blade, mop, or other surface-engaging member or applicator could also be employed. It is to be understood that the description and drawings are in all cases to be interpreted as illustrative of the invention rather than as limiting the scope thereof, and it will be apparent that various equivalent changes may be made in the various elements which comprise the invention, without departing from the spirit thereof or the scope of the appended claims.

What I claim is:

1. In a washing implement, a handle, a surface engaging head therefor mounted thereon for generally pivotal movement relative thereto, means for supplying liquid to said head, and means associated with said handle and actuated by the pressure of the liquid feeding to said head for holding the head in a given position of relative adjustment to the handle.

2. In a washing implement, an elongated handle, a surface engaging head therefor mounted for generally pivotal movement relative thereto, means associated with the handle for feeding liquid, under pressure, to one end thereof and feeding it thence to said head, and pressure actuated means movable under pressure of the liquid into engagement with said head to hold the same in a given position of adjustment relative to the handle when pressure is applied to said means.

3. In a washing implement, an elongated handle provided with a liquid passage therein, a surface engaging head pivotally mounted on the outer end of said handle, a line connecting said passage and head to transmit liquid from said handle to said head, and means at the pivoted handle end of said passage movable under the pressure of said liquid into engagement with said head to hold the same in a position of angular adjustment relative to the handle.

4. In a washing implement, an elongated handle with a liquid passage therein, a brush head including a brush with bristles pivotally mounted on one end of said handle, a reservoir on the brush and provided with spray openings for feeding liquid to the bristles thereof, an arcuate member on said head having spaced apart openings therein, a plunger in the pivoted handle end of the passage in said handle and movable under the pressure of said liquid into one of the openings in said arcuate member to hold the brush head in a given position of angular adjustment relative to the handle, valve means on the handle for shutting off the supply of water proceeding therethrough, means retracting the plunger when the liquid supply is shut off, and a line leading from the passage in said handle to the reservoir on said brush.

5. In a washing implement, an elongated tubular, hollow handle adapted to be connected to a source of liquid under pressure, the front end of said handle being closed,

10 a clevis on the front end of said handle, a brush head pivotally connected to the clevis on said handle to swing with relation thereto, an elongated reservoir on said brush head having openings along the lower side thereof to spray liquid to the front portion of said brush head, an arcuate member on said brush head having circumferentially spaced notches therein, a plunger in said handle with one end thereof extending through the closed front end of said handle, a line communicating with the interior of said handle rearwardly of said plunger and connected to the reservoir on said brush head, a shut off valve on said handle operable to permit liquid to flow through said handle, the pressure of said liquid forcing said plunger into one of said notches and locking the brush head in a given angular position relative to said handle, and means for returning said plunger to original position when the pressure is cut off.

15 6. The combination defined in claim 5 in which said notches comprise tapered bores and the front end of said plunger is tapered to engage therein.

20 7. In a washing implement, a brush comprising a body with bristles, a clamp plate for said brush including front and rear lapped plates, each having a flange extending across the sides of said body and hooking thereunder, a housing on the rear plate having a semi-circular upper end, a tongue on the front plate extending into the housing and having a nut rigid thereon, an adjusting member having threaded engagement with said nut and housing, an elongated, transverse reservoir on the flange of said

25 front plate having openings in the lower portion thereof arranged to direct streams of liquid to the front bristles of said brush, an elongated, tubular, hollow handle adapted to be connected to a source of liquid under pressure, the handle having a closed front end, a plunger in said handle with its front end projecting through the closed end thereof, the upper of said housing having circumferentially spaced notches therein to accommodate the projecting end of the plunger, a tubular clevis provided on the front end of said handle surrounding the extending end of the plunger and pivotally connected to said housing, spring means normally maintaining said plunger out of engagement with the semi-circular upper end of said housing, a flexible tube leading from the interior of said handle rearwardly of said plunger to the reservoir on said front plate, and a shut off valve on said handle operable to permit the pressure of the liquid to force said plunger forwardly into one of said notches and positively lock said brush in a position of angular adjustment relative to said handle.

30 8. In a washing implement, a handle, a surface engaging head mounted for angular movement relative to said handle, means for supplying liquid to said head, and means on one of the handle and head actuated by pressure of the liquid feeding to said head for holding the head in a given position of adjustment relative to the handle.

35 9. The combination defined in claim 8 in which said means comprises a latch pressed into engaged position by the said pressure of the liquid, and means is provided for normally urging said latch to disengaged position.
